UNITED STATES PATENT OFFICE.

JAMES V. MATTHEWS, OF HARRISBURG, PENNSYLVANIA.

CHAIN-SECURING DEVICE.

SPECIFICATION forming part of Letters Patent No. 535,015, dated March 5, 1895.

Application filed November 15, 1894. Serial No. 528,865. (No model.)

To all whom it may concern:

Be it known that I, JAMES V. MATTHEWS, a citizen of the United States, residing at Harrisburg, in the county of Dauphin and State 5 of Pennsylvania, have invented a new and useful Chain-Securing Device, of which the following is a specification.

This invention relates to an appliance for attachment to the vests or other parts of a 10 gentleman's apparel its purpose being to provide means for connecting the ends of watch chains, whereby the disadvantage of having to connect them to button-holes in the vest is avoided.

15 Ordinarily the chains of gentlemen's watches are provided at their outer ends with cross-bars adapted to be engaged with the button-holes of their coats or vests in the operation of securing the chain. Now this manner of attaching the chain is disadvantageous, in so much as the location of the button-hole often prevents the connection of the chain in an advantageous way, and makes it appear cumbersome and unhandy.

25 Now it is the object of my invention to overcome this disadvantage in a way more effective than those heretofore proposed.

To this end my invention consists in an ornamental front plate provided on its inner 30 side with a securing safety-pin, and at a point above said pin, or at the upper portion of said plate, with an eye to which a chain or cord may be connected. This chain or cord is adapted to project down the under side of the 35 plate, and below the same, so that the watch-chain may be connected to it; and in order that the chain or cord may be held from unnecessary movement, the lower inner side of the plate is provided with a guide through 40 which the chain passes, and by which said movements are prevented. It is my purpose and practice to variously ornament the plate so that it will present a beautiful appearance, and so that it may be used as an emblem for 45 societies and colleges.

In the drawings my invention is fully illustrated; and therein—

Figure 1 represents a perspective view of the device, showing it applied as in practice, 50 and showing a watch-chain attached thereto; Fig. 2, a perspective view of the rear portion of the plate, showing the devices which are applied thereto and illustrating the relation of the chain or cord aforesaid therewith; Fig. 3, a view showing a variation in the shape of 55 the face plate, and how it may be used as an emblem or badge as aforesaid.

The reference numeral 1 indicates the front plate, which is shown in Figs. 1 and 2 to be shaped square, and which may be formed of 60 any suitable material, such as gold, silver, or the like. Secured to the rear side of the plate 1, and extending adjacent to and parallel with each of the four edges thereof, is the wire 2, which is provided to permit the attachment 65 of those devices carried by the front plate. This wire is preferably secured to the plate 1 by soldering it thereto, as this is the only practicable means. The equivalent of the wire 2 may, however, be found in a rib or 70 flange formed integral with the front plate, as will be obvious.

Soldered to the wire 2, and at the upper portion thereof, is the wire 3, which proceeds inwardly and thence transversely parallel with 75 the plate 1 and with its upper edge, its middle being formed with an eye 4. This eye 4 is produced by looping the wire 3, as will be understood from Fig. 2 of the drawings. The eye 4 is disposed downwardly from the wire 80 3, and this, while preferable for the sake of convenience and ease of operation, is not essential.

Located midway the plate 1, and on the rear side thereof, is the pin 5, which has its inner 85 end secured to one side of the plate 1, and formed with a coil 6, whereby it is given a spring tendency. The free end of the pin 5 projects to and slightly beyond the opposite edge of the plate 1, and there co-operates 90 with the hook 7, which is rigidly secured to the wire 2 at that point, and which projects horizontally and inwardly. The inner end of the pin 5, at the coil 6, is secured to the wire 2 at a point opposite the hook 7, or midway 95 the plate 1.

Located at the lower extremity of the plate 1 is the loop 8, which is formed of a length of wire having its ends soldered to the wire 2 at the lower extremities of the vertical portions 100 thereof. From the ends of this wire the same extends inwardly and thence horizontally parallel with the plate and with the lower edge thereof. The inward extent of the loop

8, or its width, is approximately equal to the distance which the eye 4 has from the plate. In fact, the eye 4, pin 5, and loop 8 are all practically vertically aligned.

5 Connected to the eye 4, and extending parallel with the rear side of the plate 1, and down in front of the pin 5 and through the loop 8, is the cord or chain 9, which may be of any kind, either an ornamental chain or a 10 braided silken cord, and which has its lower end provided with a loop, so that the free end of the watch-chain 10 may be passed through it and so that the usual bar 11 thereof may bind with it and effect the connection of the 15 chain.

15 It will be observed that the attachment and arrangement of the cord or chain 9 will permit it to have a limited transverse swing, which attribute is highly advantageous. On 20 the other hand, it is equally apparent that no unnecessary or disadvantageous movement will be allowed the said cord or chain, owing to the operation of the loop 8, the structure of which has been before explained.

25 The purpose of the wire 2 is to provide means for connecting the various parts of my invention to the front plate. Were it not for this device, it would be decidedly inconvenient and impracticable to attach them to the 30 front plate directly, since it would be necessary to form on the said parts foot-like portions taking the place of the wire 2. These will be both troublesome and expensive, as will be apparent without further explanation.

Fig. 3 shows the front plate formed in the 35 shape of a shield, and ornamented with the elements of the American flag, and illustrates how the said plate may be shaped in conformity with various badges and emblems, and may be used to carry such emblems. This 40 attribute makes the invention capable of a two-fold use, and adds to its efficiency to a very great degree.

It will be understood, of course, that the design of Fig. 3 does not exhaust the designs 45 which my invention is susceptible of receiving, and that they could be varied indefinitely without any change in the substantial portions of the device.

Having described the invention, I claim— 50

A chain-securing device, consisting of a front plate provided at its rear side and near the upper edge thereof, with an eye, and having, near its lower edge and at its rear side, a guiding loop, a cord or chain connected to the 55 eye and passing through the guiding loop and projecting below the front plate, and means secured to the rear side of the front plate whereby it may be attached to an article of apparel, substantially as described.

In testimony that I claim the foregoing as my own I have hereto affixed my signature in the presence of two witnesses.

JAMES V. MATTHEWS.
